United States Patent Office

Des. 184,612
Patented Mar. 17, 1959

184,612

PANTIES

Ruth F. Emmet, Dover, Del.

Application March 27, 1958, Serial No. 50,210

Term of patent 14 years

(Cl. D3—17)

I claim:

The ornamental design for panties, as shown.
